UNITED STATES PATENT OFFICE.

CHARLES G. AVERY, OF CHICAGO, ILLINOIS.

FLAT-IRON.

No. 873,202.

Specification of Letters Patent.

Patented Dec. 10, 1907.

Application filed March 30, 1906. Serial No. 308,915.

To all whom it may concern:

Be it known that I, CHARLES G. AVERY, a citizen of the United States, residing at Chicago, in the county of Cook and State of Illinois, have invented certain new and useful Improvements in Flat-Irons, of which the following is a specification.

This invention relates to new and useful improvements in flat irons, and has for its objects, first, to produce a sad iron having openings in the bottom through which a moistening liquid may be distributed to the cloth at the time of pressing; second, to afford facilities for steaming the cloth when heat and pressure are applied to it; third, to provide means for an ample supply of a moistening liquid for continuous use without frequent refilling of the same.

With these and other objects in view my invention consists of the novel features and combination and arrangement of parts hereinafter more specifically described, illustrated in the drawings, and particularly pointed out in the claims hereunto appended.

In describing the invention in detail reference is had to the accompanying drawing forming a part of this specification, wherein like numerals of reference indicate corresponding parts throughout the several views and in which

Figure 1 is a side elevation, Fig. 2 is a bottom plan of the forward part of the iron, Fig. 3 is a horizontal section near the bottom and forward end of the iron, Fig. 4 is a front elevation somewhat enlarged, and Fig. 5 is a detail view of the connection of the stem with the valve crank.

To point out one use of my invention I have shown an electrically heated flat iron, with such modifications and additions as will make plain my improvements.

Referring to the drawings by reference numerals, 8 denotes the body of the iron, and 9 the handle thereof.

10 represents a tank, positioned at the rear of the handle.

11 is the pipe leading from the tank to the forward part of the iron, and 12 is the portion of 11 made to conform to the front end 50 of the iron. At 13 this pipe is suitably bent, or an elbow is employed to be inserted into the outer end of the water passage 14. At 15 in the pipe 11 is an ordinary valve with rod 16, which is adapted to be pushed downward by the thumb of the hand grasping the handle to open the valve. The tension of

spring 17 tends to keep the valve in closed position. The water distributing passage 14 preferably is small and extends parallel with and a short distance from one side of the toe 60 of the iron, and branch 18 of the passage extends similarly along the other side of the toe of the iron. At suitable distances apart are perforations 19 through the bottom of the iron and opening into the passages 14, 18. 65

The pipe at 13 may be suitably bent, or it may have an elbow of proper angle, and be sufficient in diameter to fit the outer end of passage 14 and be held in place by frictional contact with the wall of the passage. If desired the outer end of passage 14 may be provided with a female thread and the end of the pipe or elbow at 13 may be male threaded. 70

21 is a cap upon the filler neck 20 of the tank. 75

The outer end of the passage 18 may be plugged by any suitable means and material, as at 22.

The base or portion 23 of the iron is of solid steel, or other metal, pointed at the forward end and of any desired size and weight. 80

Lugs 24 and 25 are perforated vertically to afford a position for the rod 16. Pin 32 in rod 16 above the spring 17 presses down the spring when 16 is operated, and when the 85 force of the thumb is removed returns the stem to normal and closed position of the valve.

26 is the foot (see Fig. 4) of rod 16, with slot 27 in which travels pin 28 of the crank 90 29 of the valve shaft 30.

Fig. 4 is an enlarged detail showing the foot 26 and crank 29 in closed position of the valve. 31 is the usual wire connections of an electrically heated iron. 95

As my invention modifies only the base of the iron no detailed description or illustration is given of the construction of an electrically heated iron.

In work requiring considerable water for continuous use through a day or more I provide the well known rubber bag or fountain and the usual rubber tube forced on the neck 20 of the tank after the cap 21 is removed, and the bag or fountain suspended from the 100 gas fixture or other place in the room. This means of supplying a quantity of water is so well understood in the arts that it is not deemed necessary to show it in detail in the drawings. 105

It is desirable that a supply of water be kept on the iron at all times in order to avoid 110

passing cold water through the passages 14, 18; therefore, when the rubber bag is used I prefer also to retain the use of tank 10.

In use of my invention when the operator 5 desires to apply moisture or steam to the cloth the rod 16 will be depressed by the thumb when the valve 15 will be opened and the water flow into passages 14, 18, and be distributed to the cloth through perforations 19. The application of moisture or steam being under the control of the operator and will depend upon the use of the valve, and the rapidity with which the iron is advanced over the cloth.

15 It will be apparent that I afford facilities for vaporizing the liquid before it is applied to the surface of the cloth, and for this purpose pipe 11, 12 and 13 and passage 14 with its branch 18 of small diameter and limited 20 capacity, are provided. It is obvious, with a hot iron, the liquid instantly will become steam and will emerge from the passage and perforations exerting a force in all directions. This novel construction therefore enables 25 me at will to apply steam to the whole sur-

face to be pressed and simultaneously with the pressing. It is evident, with my construction, the cloth will not be scorched or burned in the case of a too hot iron, as the steam is applied to the entire surface beneath the iron, while with other forms which moisten the seam or selvage only, a too hot iron will scorch or burn the remaining surface under the iron.

30 Having thus fully described my invention 35 what I claim as new, and desire to secure by Letters-Patent, is

The combination of a flat iron body having a small water passage and perforations in the bottom and near the forward end thereof, a 40 valve-controlled pipe of small dimensions, and means adapted to supply water to the pipe.

In testimony whereof I affix my signature in presence of two witnesses.

CHARLES G. AVERY.
